(57) **CLAIM**

The ornamental design for a "sliding bracket", as shown and described.

DESCRIPTION

FIG. 1 is a perspective view of the sliding bracket showing my new design;

FIG. 2 is a top plan view of the sliding bracket, the opposite view being a mirror image thereof;

FIG. 3 is a front elevational view of the sliding bracket;

FIG. 4 is a rear elevational view of the sliding bracket;

FIG. 5 is a left side view of the sliding bracket; and,

FIG. 6 is a right side view of the sliding bracket.

The claimed design is shown broken away to indicate indeterminate length.
